ATTORNEY

UNITED STATES PATENT OFFICE.

DAVID DAVIS, OF BRITTON, SOUTH DAKOTA.

WINDOW-PROTECTOR.

1,314,510.

Specification of Letters Patent. Patented Sept. 2, 1919.

Application filed August 10, 1917. Serial No. 185,599.

To all whom it may concern:

Be it known that I, DAVID DAVIS, a citizen of the United States, residing at Britton, in the county of Marshall and State 5 of South Dakota, have invented certain new and useful Improvements in Window-Protectors, of which the following is a specification.

My invention relates to new and useful 10 improvements in a window protector and more particularly to a protector for cashier's or bank teller's window.

The principal object of the invention is the provision of a protector adapted to be 15 normally held above the window and which may be lowered to cover the window.

A further object is the provision of a 20 catch for holding the protector in raised position and means for releasing the catch to allow the protector to drop.

Still another object is the construction 25 of the protector in sections hingedly connected whereby they will fold to allow the protector to be held in compact form and in a small space.

With these and other objects in view, the invention consists in the novel details of construction and arrangement of parts which will be more clearly understood from 30 the following description and drawing, in which—

Figure 1 is a front elevation.

Fig. 2 is a transverse vertical section 35 showing the protector in raised position, and

Fig. 3 is a transverse vertical section illustrating the protector in lowered position.

In the drawing the numeral 1 indicates 40 the top of the counter supported upon suitable legs 2 and 3 indicates the front of the counter. Standards 4 extend from the top of the counter and are connected at the top by means of a suitable cross bar 5 and a grating 6 is connected between the top 1 and the bar 5 so as to leave an opening 7 through which money or other articles is adapted to be passed.

Brackets 8 are secured to the inner faces 50 of the standards 4, and a rod 9 is carried by the brackets and my protector is adapted to be secured to this rod. The protector comprises a plurality of sections 10 hingedly connected at 11 and are preferably constructed of metal. The sections 10 are 55 adapted to be folded one upon the other as more particularly illustrated in Figs. 1 and

2 of the drawings so that the protector may be held in compact form and take up little space.

Brackets 12 are secured to the top of the 60 cross bar 5 and have a horizontal rod 13 rotatably mounted therein. This rod 13 is provided on the outer end with a right angled extension 14 terminating in an eye 15 the purpose of which will be presently described. The opposite end of the rod 13 is provided with a vertical extension 16 having the right angled extension 17 formed thereon with the downwardly extending end portion 18. The vertical portion 16 is of 70 such a length whereby the right angled extension 17 will overlie the top of the hinged sections of the protector, when in raised position, as illustrated in Figs. 1 and 2 of the drawing, and the curved end portion 18 will 75 extend downwardly whereby the sections are held between the vertical sections 16 and downwardly extending portion 18.

A foot treadle 19 is pivotally connected 80 at 20 beneath the counter and a wire or other flexible member 21 is connected to the treadle 19 in front of the pivot point, and to the eye 15 formed on the right angled extension 14 of the horizontal rod 13. While I have illustrated the treadle pivoted 85 in the position shown it will be understood that I do not desire to be limited to the specific form of treadle or the position in which it is placed but it might be made of different form and positioned any place just 90 so as to be within the easy reach of the party behind the counter who might desire to operate the protector.

It is thought that from the above detailed description that the advantages and mode of 105 operation of my device will be clearly understood. The invention is intended for the protection of a cashier or bank teller who usually have a considerable amount of money on the counter before them. A great 100 many hold-ups have occurred by robbers appearing before the window and ordinarily there is no protection or means for closing the window to prevent the stealing of the money while the person behind the counter 105 has his hands up. At the same time if a protecting device is to be operated the operator must be able to operate the same without being detected by the robber and it is the object of my invention not only to have a 110 protector which will close the window but which may be operated without detection

from in front of the window. Normally the protector will be held above the window as is illustrated in Figs. 1 and 2 of the drawing, the sections being folded one upon the other 5 and held as shown. Should a robber appear before the window the person behind the counter may engage the foot treadle 19 by the foot and by pressing downwardly thereon it will swing upon the pivot point 20 and 10 draw upon the wire 21, lower the right angled extension 14 and rotate the horizontal rod 13 thereby drawing the vertical extension 16 backward to raise the curved end portion 18 and thereby allow the protector 15 to drop into the position as illustrated in Fig. 3 of the drawings. As has been previously stated the protector is preferably formed of metal so as to resist blows and when lowered the opening of the window is 20 entirely closed and the cashier or bank teller will be entirely safe.

Having fully described my invention, what I claim as new and desire to secure by Letters Patent is:

- 25 1. A window protector comprising a plurality of hinged sections adapted to be folded one upon the other, said protector being hingedly supported at the upper part of the window frame, journals on said frame, a
- 30 latch mounted in said journals comprising a horizontal shaft, an arm extending at right angle to the shaft, said arm extending vertically in front of the folded hinged sections, an extension on said arm passing over the

said sections and terminating in a hook at 35 the top and rear of the sections, a horizontal angular extension on the opposite end of the shaft, a foot treadle and means connecting the treadle with the last mentioned extension.

40 2. A window protector comprising a plurality of hinged sections adapted to be folded one upon the other, said hinged sections being pivotally secured to the window casing and folded parallel to the face thereof, a catch pivotally connected to the window casing and adapted to overlie the folded sections, said catch engaging the outermost section whereby the sections are held in their folded position, and means for releasing the 45 catch.

45 3. A window protector comprising a plurality of hinged sections adapted to be folded one upon the other, a catch pivotally connected to the window casing and adapted 50 to overlie the folded sections, said catch comprising a horizontal rod having a vertical extension and a right angled extension formed on the vertical extension and having a hooked end, and means for releasing the 55 catch.

In testimony whereof I affix my signature in presence of two witnesses.

DAVID DAVIS.
